UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

PROCESS AND APPARATUS FOR CONVERTING OILS.

Application filed October 8, 1921. Serial No. 506,225.

This invention relates to improvements in process and apparatus for converting oils and refers more particularly to a process in which preheated gas is introduced to the vaporizing oil body to accelerate and increase the yield of the generated vapors. Among the salient objects of the invention are to provide a process in which oil is heated to a cracking temperature in the heating zone and permitted to crack and vaporize in an enlarged vapor zone, wherein, during vaporization, heated gases are caused to percolate through the oil body for the purpose of maintaining the vaporizing oil at a proper conversion temperature, agitating the oil to assist in maintaining the separated free carbon in suspension in the unvaporized oil and to accelerate and increase the volume of vapors generated; to provide a process in which the percolation of heated gases through the vaporizing oil body obviates the necessity of externally heating the vaporizing zone to maintain it at a proper conversion temperature; to provide a process in which the injection of this heated gas permits a somewhat lower temperature being maintained in the heating zone, reducing thereby the carbon collection in the heating coils and difficulties caused thereby; to provide a process which utilizes more efficiently the heat applied to the system and affords an increased and more uniform yield and permits of the operation continuously of the process for a greater period of time than has been heretofore the practice in common types of conversion apparatus.

Reference is made to my co-pending application Serial No. 381,921, filed May 17, 1920, which discloses certain subject matter found in this application.

The single figure in the drawing is a dia-grammatic side elevational view of the apparatus.

Referring in particular to the drawing, the raw oil is introduced through the inlet pipe 1 to the top of the dephlegmator 2, and flows downwardly therethrough in an opposed direction to the oil vapors which are refluxed by coming in intimate contact with the incoming cool raw oil. The oil, with what condensate it may collect in the refluxing or fractional condensing column 2 is drawn off through the line 3 controlled by a valve 4 and is charged by means of a pump 5 through the charging line 6 to the heating coil 7 mounted in the furnace 8, the latter being preferably heated by means of gas burners 9. The oil, after being raised to a cracking temperature, is passed through the transfer line 10 to the vaporizing chamber 11 where it collects and is permitted to vaporize in a substantial body, the level of the oil in the insulated chamber being regulated by the residuum drawoff line 12 controlled by a valve 13. The vapors generated in the vaporizing chamber pass off to the line 14 controlled by a valve 15 and are refluxed as explained in the dephlegmator or fractional condensing apparatus 2. The still uncondensed vapors pass over from the reflux condenser through the line 16 to a water condenser 17 and are collected as distillate in the receiver 18, the latter being equipped with a pressure gauge 19, and liquid level gauge 20 and a drawoff line 21 controlled by valve 22. The uncondensable gas which is collected in the receiver may be drawn off through the line 23 regulated by a valve 24 and charged by a pump 25 through the line 26 in which is interposed a valve 27 to a heating coil 28 mounted in a heater 29 which receives the heated gases from the furnace through a flue 30 controlled by a damper 31, the expended gas passing off through the stack. The gas, after being heated in the heating coil 28 is directed through a line 32 in which is positioned a check valve 33 and a pyrometer 34 and is percolated through the oil body maintained in the vaporizing chamber by means of a perforated pipe 35 submerged therein. The heated gas bubbling up through the oil body has a peculiar chemical effect, which besides promoting the vaporization of the oil, produces a better quality and more uniform distillate in the receiver. The agitation caused by the gas thoroughly intermixes the oil so that a uniform temperature is produced throughout and the heating effect of the gas obviates the necessity of externally heating the vaporizing chamber in order to maintain the oil body at a desirable conversion temperature. It is apparent that the heat employed to heat the gases passing through the coil 28 is the escaping or exhaust heat from the main furnace. Obviously the heating gases from this furnace when they reach the coil 28 are at a temperature lower than the temperature

of the gases impinging against the heating coil 7 of the cracking still. By this method the oil in the reaction chamber is, as stated "maintained" at its cracking temperature but the transfer temperature of this oil is not substantially raised for reasons that are apparent from this specification.

The agitation of the oil, due to the gas, holds a substantially greater portion of the free carbon in suspension, which may be drawn off from time to time or continuously from the residuum line 12, thus limiting the collection of baked carbon in the vaporizing chamber so that the apparatus may be run for a greater length of time than has heretofore been possible as a greater amount of the carbon is drawn off with the unvaporized oil and residuum. The increased reaction caused by the injection of heated gases facilitates the vaporization of the oil in the reaction or vaporizing chamber and permits of the maintenance of a lower temperature in the heating coil. This latter advantage is of substantial importance due to the fact that the lower temperature in the heating coil reduces the deposition of carbon therein, a factor which is important in the cleaning and efficient operation of the process. In order not to cause deposition of carbon in the cracking coils, it is necessary to limit the heat therein to a point in each cycle or to a temperature that will give only a certain yield of gasoline and also a certain total percent of refluxing oil. From the total evaporated oil is obtained a yield of pressure distillate, the remainder being the portion that is refluxed back for further treatment and cracking.

It is evident from this that the total final yield of gasoline is dependent upon the percent of raw oil represented in the reflux oil. It is also evident that the percent of reflux oil cannot be increased without increasing the temperature of the oil in the cracking tubes, as the reflux oil requires a higher temperature for conversion. This higher temperature will cause precipitation of carbon on the walls of the cracking tubes, if care is not taken in the heating. With the use of gas introduced to the vaporizing chamber, the oil in the heating tubes would be submitted to a lower temperature for the reason that when the oil in the expansion chamber is agitated with gas, a greater percentage is vaporized therefrom than when unagitated, the oil in both cases being the same temperature. This increased evaporation gives a greater percent of reflux oil which is returned to the cracking tubes and thus results in the final yield of gasoline being very much increased and without the necessity of subjecting the oil in the cracking tubes to higher temperatures. Such treatment will leave the cracking

tubes, transfer lines and vapor lines comparatively free of carbon, the carbon in the apparatus accumulating almost entirely in the expansion chamber. If the uncondensable gas from the receiver is insufficient, extraneous gas may be introduced from any convenient source through the line 36 controlled by a valve 37.

I claim as my invention:

1. A process of converting hydrocarbon oils, which comprises passing a stream of oil through a cracking zone where said oil is subjected to a cracking temperature, in delivering the highly heated oil to an insulated vapor chamber located outside of the cracking zone and in which chamber a pool of liquid oil collects, in discharging vapors from said chamber to a dephlegmator, in returning reflux condensate from the dephlegmator to the oil stream passing through the cracking zone, in discharging uncondensed vapors from the dephlegmator to a final condenser and receiver, in removing incondensable gases from said receiver, in heating said gases, and in then passing the heated gases into a conduit immersed in the liquid oil in the vapor chamber, in discharging the gases from said conduit into said oil, and in maintaining a superatmospheric pressure on the oil in the cracking coil and in said vapor chamber.

2. An oil cracking process consisting in continuously advancing a restricted stream of oil through a heating tube disposed within a heating furnace where said oil stream is heated to a cracking temperature, in delivering said stream of oil while at a cracking heat to an enlarged reaction zone without permitting the escape of any fractions of said oil stream, in maintaining a body of heated oil in said reaction zone where conversion thereof occurs, in promoting the conversion of the oil in said enlarged reaction zone by introducing heated incondensable gases from the process thereto to percolate through the oil body maintained therein and undergoing conversion, in continuously removing liquids and vapors from said enlarged reaction zone, and in maintaining a superatmospheric pressure on the oil undergoing conversion in said heating coil and in said enlarged zone.

3. An oil cracking process consisting in continuously advancing a restricted stream of oil through a heating tube disposed within a heating furnace where said oil stream is heated to a cracking temperature, in delivering said stream of oil while at a cracking heat to an enlarged reaction zone without permitting the escape of any fractions of said oil stream, in maintaining a body of heated oil in said reaction zone where conversion thereof occurs under a cracking heat, in promoting the conversion of the oil in said enlarged reaction zone by introducing

- heated incondensible gases thereto to percolate through the oil body undergoing conversion, in subjecting vapors generated from converted oil to reflux condensation, in re-cracking the reflux condensate by introducing the same to the inlet side of the heating coil, and in preventing the return of unvaporized residue from the enlarged reaction zone to said heating coil, and in maintaining a superatmospheric pressure on the oil undergoing conversion in said heating coil and said enlarged reaction zone.
4. An oil cracking process consisting in continuously advancing a restricted stream of oil through a heating tube disposed within a heating furnace where said oil stream is heated to a cracking temperature, in delivering said stream of oil while at a cracking heat to an enlarged reaction zone without permitting the escape of any fractions of said oil stream, in maintaining a body of heated oil in said reaction zone where conversion thereof occurs, in promoting the conversion of the oil in said enlarged reaction zone by introducing heated incondensible gases from the process thereto to percolate through the oil body maintained therein, in subjecting the vapors generated from the converted oil to reflux condensation, in aiding in the condensation of said vapors by passing charging oil in heat conductive relation with the vapors, in introducing the preheated charging oil and the reflux condensate to the inlet side of the heating coil, and in preventing the return of unvaporized residue from said enlarged reaction zone to the heating coil, and maintaining a superatmospheric pressure on the oil undergoing conversion in said heating coil and said enlarged reaction zone.
5. An oil conversion process consisting in passing a restricted stream of oil through a heating coil disposed within a heating furnace, in heating such oil by furnace gases during its passage through said coil to a cracking temperature, in delivering the stream of heated hydrocarbons to an enlarged reaction zone where a body of oil is maintained, in promoting the vaporization of the heated oil in said reaction zone while conversion thereof is occurring by introducing heated hydrocarbon gases to said reaction zone to physically commingle with the oil therein, in maintaining a superatmospheric pressure on the oil stream and on the oil in said reaction zone, in discharging vapors from the reaction zone for reflux condensation, in re-cracking the reflux condensate by admitting the same to the inlet side of the heating coil, and in withdrawing unvaporized residue from the reaction zone without again admitting the same to the heating coil.
6. An oil converting process consisting in heating oil to a cracking temperature while
- passing in a restricted stream through a heating zone, in collecting an enlarged body of such oil in a reaction zone where said oil undergoes conversion, and in aiding in the conversion of the oil in the enlarged reaction zone by introducing heated incondensible gases from the process to said zone to commingle with the oil body therein without substantially raising the transfer temperature of the oil introduced to such enlarged zone, and in maintaining a superatmospheric pressure on the oil undergoing conversion.
7. An oil cracking process consisting in continuously advancing a restricted stream of oil through a heating tube disposed within a heating furnace where said oil stream is heated to a cracking temperature, in delivering said stream of oil while at a cracking heat to an enlarged reaction zone without permitting the escape of any fractions of said oil stream, in maintaining a body of heated oil in said reaction zone where conversion thereof occurs, in promoting the conversion of the oil in said enlarged reaction zone by introducing heated incondensable gas from the process thereto to percolate through the oil body maintained therein, in continuously removing liquids and vapors from said enlarged reaction zone, and in maintaining a superatmospheric pressure on the oil undergoing conversion in said heating coil and in said enlarged zone.
8. An oil conversion process consisting in passing a restricted stream of oil through a heating coil disposed within a heating furnace, in heating such oil by furnace gases during its passage through said coil to a cracking temperature, in delivering the stream of heated hydrocarbons to an enlarged reaction zone where a body of oil is maintained, in promoting the vaporization of the heated oil in said reaction zone by introducing heated hydrocarbon gas to said reaction zone to physically commingle with the oil therein, in maintaining a superatmospheric pressure on the oil stream and on the oil in said reaction zone, in discharging vapors from the reaction zone for reflux condensation, in re-cracking the reflux condensate by admitting the same to the inlet side of the heating coil, and in withdrawing unvaporized residue from the reaction zone without again admitting the same to the heating coil.
9. In an apparatus for treating hydrocarbon oils, the combination with a heating zone, of a separate reacting zone connected therewith and located outside of said heating zone, means for condensing and collecting the vapors generated in the heating and reacting zones, and means for introducing the uncondensable gases produced directly into the body of oil in the reacting zone through a conduit immersed in said body to agitate the oil body to prevent carbon from

- depositing on the walls of the reacting zone and to maintain the carbon in suspension in the residuum to be withdrawn therewith from the reacting zone.
- 5 10. A process for treating hydrocarbon oils, consisting in subjecting the oil to a cracking temperature in a heating zone by passage through a heating coil disposed therein, in directing the oil constituents 10 from said coil to a separate reaction zone located outside of the heating zone, in drawing off and condensing the vapors from the reaction zone and injecting the uncondensable gas produced in the system directly into the body of oil in the reaction zone to percolate through said body and prevent adherence of free carbon to the walls thereof and to cause such carbon to remain in suspension in the residuum, and in withdrawing the re-
- siduum and suspended carbon from the reacting zone.
11. The process of treating hydrocarbon oil, consisting in heating a stream of oil to a conversion temperature, in transferring the heated oil constituents to an enlarged reaction zone where a body of liquid oil is maintained, in which zone conversion of the oil occurs, in introducing into the body of liquid oil maintained in said enlarged zone gases produced in the process under pressure to promote the reaction of the oil therein and to keep the carbon in suspension in the residual oil, in withdrawing the products of conversion from said reaction zone, and in maintaining a superatmospheric pressure on the oil stream and the body of oil in said enlarged reaction zone. 20
